DESIGN FOR AN END PLATE FOR FLUORESCENT LIGHTING FIXTURES

John Carulli, Branford, Conn., assignor to The Miller Company, Meriden, Conn., a corporation of Connecticut

Application September 29, 1945, Serial No. 122,408

Term of patent 7 years

(Cl. D48—23)

To all whom it may concern:

Be it known that I, John Carulli, a citizen of the United States of America and a resident of Branford, in the county of New Haven and State of Connecticut, have invented a new, original, and ornamental Design for End Plate for Fluorescent Lighting Fixtures, of which the following is a specification, reference being had to the accompanying drawing, forming a part thereof.

In the drawing:

Figure 1 is a side elevational view of the end plate for fluorescent lighting fixtures, showing my new design;

Figure 2 is an edge view of the same;

Figure 3 is an inverted plan view of the same; and

Figures 4 and 5 are sections on the lines 4—4 and 5—5 respectively, of Figure 1, looking in the direction of the arrows.

I claim:

The ornamental design for an end plate for fluorescent lighting fixtures, as shown.

JOHN CARULLI.
